UNITED STATES PATENT OFFICE.

REGINALD FRANK KRALL, OF LONDON, ENGLAND, ASSIGNOR TO WOODALL-DUCKHAM
(1920) LIMITED, OF LONDON, ENGLAND, A BRITISH COMPANY.

APPARATUS FOR SEPARATING SOLIDS FROM LIQUIDS.

Application filed April 24, 1926, Serial No. 104,460, and in Great Britain August 28, 1925.

In British Patent No. 219,651 there is described a drying apparatus in which a supply hopper delivers the material to be dried on to a distributing plate mounted on a vertical shaft which is co-axial with a substantially conical screen, also mounted, larger end downwards, on the shaft. The shaft being rotated the material is thrown off the plate against the screen down which it travels, preferably in steps as described in the said specification, becoming dried during its progress. At the bottom of the screen it is thrown against the wall of a stationary hopper wherein it collects.

The present invention relates to improvements in apparatus of this kind for the purpose of facilitating its operation and rendering it more efficient.

In the known construction it was found necessary to provide the necessary clearance between the rotating screen and the collecting hopper by means of a tortuous passage in order to avoid entry of the water spray, which fills the closed casing around the screen, through the clearance into the hopper, where it would re-wet the material. It was found, however, that, since dust would enter the clearance and become caked when the machine was idle, difficulties were encountered when the machine was to be re-started and which required a high expenditure of power.

An object of the present invention is to overcome the disadvantages associated with the known type of apparatus referred to. For this purpose, the clearance between the lower part of the rotating screen and the hopper which receives the dried material is formed between a pair of rings, thin in the radial direction, one of which depends from the screen and the other of which extends upwardly from the hopper, with the lower edge of the depending ring in close proximity to the upper edge of the upstanding ring. The clearance between these two rings may be reduced to such small dimensions that the quantity of caked dust existing in it when the machine is to be re-started cannot create any difficulty.

With this form of clearance it is desirable that there should be a separate surface for collecting the water expelled from the material and for this purpose the invention provides a stationary or rotating non-perforated plate extending around the rotary screen.

The accompanying drawings illustrate machines provided with the improvements according to the invention.

Fig. 1 is a vertical section through one form and Fig. 2 is a like view of another form, the left hand side of the figure being slightly modified as compared with the right hand side. Fig. 3 is a sectional detail view.

Referring to Fig. 1, as in the known machine the material charged into the stationary hopper *a* is distributed by the rotating plate *b* against the conical screen *c* which is also rotating and is constructed in steps as indicated. From the screen the material passes into the hopper *d*, the upper part of which is alone shown in the drawing.

In the known construction the casing *e* is closed to the atmosphere; in the present case the casing has openings *f*. To act as a water collecting screen there is a non-perforated hood *g* depending from the top of the casing; the water draining from this hood falls into the trough *h*.

The joint between the bottom ring *c'* of the screen and the ring *d'* which carries the hopper *d* is shown in Fig. 3. The ring *c'* carries a depending ring *c²* and the ring *d'* an upstanding ring *d²* of the same diameter. The clearance between these rings *c²*, *d²* may be reduced to such small dimensions that the quantity of caked dust which may exist in it when the machine is to be re-started cannot create any difficulty. By setting the ring *c²* at some little distance from the periphery of ring *c'* as indicated, the clearance between rings *c²* and *d²* is sheltered from water splashing.

In the modification shown in Fig. 2 the upper part of the casing *c* is eliminated, the frame members *i* being provided merely for carrying the usual machinery guards for protecting operatives. The shaft *k* carries on arms *l* the conical non-perforated plate *m* on the interior surface of which are studs *n*; to the latter the conical screen *c* is suitably attached. Thus the plate which collects the water rotates, with the advantage that there is less splashing than when the screen is stationary.

This last-named advantage may facilitate the construction because the clearance between the screen and the collecting hopper *d* may be as large as is reasonable. In the case shown on the right hand side of Fig. 2 the lowest ring *c'* of the screen carries a conical

ring *o* which extends into the mouth of the hopper *d* with considerable clearance, the latter being protected by a similar conical ring *p* carried by the casing and extending upwards sufficiently to intercept drops from the plate *m*.

The rotary plate *m* lends itself to ready washing, and for this purpose a water-pipe *q* is arranged to discharge against the upper part of the interior surface of the plate. This involves a somewhat heavy discharge of water and the modification shown on the left hand side of Fig. 2 is preferable. Here a baffle-ring *r* to deflect the water directly into the trough *h*, is carried by the frame members *i*. A joint is constructed at *s* similar to that shown in Fig. 3.

Having thus fully described the nature of the said invention and the best means I know of carrying the same into practical effect, I claim:—

1. A drying apparatus comprising a substantially conical screen having its axis substantially vertical and its larger end extending downwardly and adapted to be rotated about its axis, means for projecting particles of material to be dried against the inner surface of the screen, means for feeding material to the said projecting means, a hopper positioned below said screen to receive dried material leaving the lower end of the screen, a ring depending from said screen, and a ring coaxial with and of the same diameter as said first-named ring and upstanding from the hopper with its upper edge in close proximity to the lower edge of the first-named ring and cooperating with the latter to form a clearance between the screen and the hopper.

2. An apparatus according to claim 1 comprising an imperforate plate surrounding and supporting the screen.

3. A drying apparatus comprising a substantially conical screen having its axis substantially vertical and its larger end extending downwardly and adapted to be rotated about its axis, means for projecting particles

of material to be dried against the inner surface of said screen, means for feeding material to said projecting means, a hopper positioned below said screen and adapted to receive dried material as it leaves the lower end of the screen, a trough surrounding the hopper and a conical ring extending upwardly from the mouth of the hopper into proximity to the lower end of the screen to divert splashes of liquid from the clearance between said mouth and the screen into said trough.

4. An apparatus according to claim 1, comprising a conical plate surrounding and spaced from the screen, a trough below the lower end of said plate, means for discharging water upon the upper part of the inner surface of said plate.

5. An apparatus according to claim 1, comprising a conical plate surrounding and spaced from the screen, a trough below the lower end of said plate, means for discharging water against the inner surface of said plate and a baffle to receive the water as it leaves said plate and direct it into said trough.

6. A drying apparatus comprising a substantially conical screen having its axis substantially vertical and its larger end extending downwardly and adapted to be rotated about its axis, means for projecting particles of material to be dried against the inner surface of the screen, means for feeding material to the said projecting means, a hopper positioned below said screen to receive dried material leaving the lower end of the screen, a ring depending from said screen and of slightly less diameter than the external diameter of the lower end of the screen, and a ring coaxial with and of the same diameter as said first-named ring and upstanding from the hopper with its upper edge in close proximity to the lower edge of the first-named ring and cooperating with the latter to form a clearance between the screen and the hopper.

In testimony whereof I have signed my name to this specification.

REGINALD FRANK KRALL.
